UNITED STATES PATENT OFFICE

2,585,702

SPECTROMETER

Robert W. Thompson, Minneapolis, Minn., and Wallace T. Leland, New York, N. Y., assignors to the United States of America as represented by the United States Atomic Energy Commission

Application June 12, 1945, Serial No. 599,066

7 Claims. (Cl. 250—41.9)

1

The present invention relates to mass spectrometers, and particularly to mass spectrometers utilizing thermionic ion sources.

In various mass spectrometer procedures, as for example, the determination of isotope abundance ratios of uranium and other heavy metals, it is necessary to employ positive ions within the spectrometer, and in the past considerable difficulty has been encountered in the provision of a satisfactory source of such ions. This difficulty is particularly serious in the case of uranium, and various rather complicated procedures, some of which necessitate the introduction of gaseous halogen compounds of uranium into the mass spectrometer during the analysis, have been used. These procedures not only are very time consuming, but in addition they can be carried out only by very highly skilled technicians. As a result, the obtaining of uranium isotope abundance ratios and similar measurements on a production schedule basis has heretofore been considered substantially impossible of attainment, despite the existing need for such determinations.

The principal object of the present invention is to provide an improved mass spectrometer which will satisfy this need and will make possible the determination of isotope abundance ratios in a relatively short period of time, without necessitating unusual skill on the part of the operator, the apparatus being thereby adapted for use in connection with routine commercial manufacturing operations.

As will hereinafter appear, this object of the present invention is accomplished by the provision of a mass spectrometer apparatus which utilizes a thermionic ion source of novel design, this arrangement contrasting with the prior known apparatus employing ion sources in which the desired positive ions were produced by bombardment of suitable gaseous compounds by low energy electrons. The improved apparatus of the present invention includes various novel and useful structural features and combinations of those features which contribute to its successful operation. These various structural features and other objects and advantages of the invention will be made more apparent by reference to the accompanying drawings and the following description of a preferred embodiment thereof. In the drawings:

Fig. 1 is a sectional view, partly in elevation, of a mass spectrometer embodying the features of our invention;

Fig. 2 is an enlarged, fragmentary sectional view, partly in elevation, of the thermionic ion

2

source and the associated beam directing and collimating apparatus forming a part of the mass spectrometer illustrated more completely in Fig. 1;

5 Fig. 3 is a sectional view, partly in elevation, taken on the line 3—3 of Fig. 2 of the internal construction;

Fig. 4 is a view, partly in plan and partly in section, taken in the direction of the arrows 4—4 of Fig. 2;

Fig. 5 is an enlarged fragmentary sectional view, partly in elevation, on the line 5—5 of Fig. 3; and

10 Fig. 6 is a circuit diagram showing the features of a control circuit for operating the spectrometer illustrated in the other figures of the drawings.

The mass spectrometer illustrated in Fig. 1 includes a glass envelope 7 which terminates at one end in a large female grind 9, through which the thermionic ion source assembly 11 is inserted by means of a complementary male grind 13. The outer envelope includes a four lead, reentrant press seal 15, through which the connections for the control potentials are made, and

15 a pumping duct 17, adapted to be connected to suitable evacuating apparatus (not shown). The other end of the envelope 7 is closed by a cup-shaped, metallic end closure 19, which is adapted to support an ion beam collimating and centering structure 21 and a metallic analyzer tube 23 which connects therewith. The metallic end closure 19 is sealed into the glass tube by a suitable glass to metal seal, various types of which are well-known to the art. The analyzer tube 23 is curved, as illustrated at 25, to conform to the curvature produced in the ion beam by a magnetic field producing structure, indicated diagrammatically at 27. A suitable ion collector 29, which includes electrical connections 31, by 20 means of which the ion beam may be monitored and its intensity measured, is provided at the end of the analyzer tube 23.

25 The thermionic ion source 11 includes a filament 33, which in one satisfactory embodiment of the invention comprises a helical coil of 8 mil (.008 inch) tungsten wire, the filament having a length, prior to stretching, of about 2.5 millimeters, and an inside diameter of 40 mils. The filament 33 when stretched has a coil length of about 4.0 millimeters, and it is suspended, as by spot-welding, upon two filament supports 35 of approximately 50 mils in diameter which pass through a conventional press seal 37 in a 14 millimeter glass tube 39, which is joined to the male grind 13 by a reentrant glass seal 41.

30 The satisfactory operation of the thermionic

ion source 11 of the mass spectrometer of the present invention is believed due in large measure to the provision of an electrostatic focusing system which coacts with the filament 33. This system includes a pair of opposed, focusing electrodes 43, each of which comprises a flat strip of a refractory metal, such as Nichrome, bent into the obtuse angle shape illustrated particularly in Fig. 5. The electrodes 43 are fastened together, with the base portions 44 thereof in spaced parallel relationship and with the other portions 45 thereof in outwardly flaring relationship, by means of glass spacers 47, glass washers 48, metallic washers 49, and suitable rivets 50. The outwardly flaring portions 45 of the two focusing electrodes 43 define a dihedral angle of approximately 90° and are adapted to be positioned with the outer periphery of the filament 33 adjacent the apex of this angle.

The focusing electrode structure is supported independently of, and adjustably relative to, the filament 33 by means of two split clamps 51 and 53, an angle support 54, and a flat support 55, all of which may be of Nichrome or other suitable refractory metal. The angle support 54 and the flat support 55 are each rigidly affixed to its clamp at one end and are spot-welded to one of the outwardly flared electrodes 43 at the other end, as illustrated. The clamps 51 and 53 are riveted or otherwise fastened together about the tube 39 so as to snugly engage that tube, yet not too tightly, to prevent the clamps from being moved along the tube 39. The arrangement described provides a stiff positive support for the focusing electrode structure, yet at the same time it permits adjustment of the position of the electrode structure relative to the filament 33. The two outwardly flaring electrodes 43 are insulated from each other, and electrical connections for the control potentials are made thereto through the supports 54 and 55.

The ion beam collimating and centering structure 21 is attached to the analyzer tube 23 and is positioned intermediate the thermionic ion source 11 and the inlet end of tube 23. The structure 21 includes a pair of rectangular slit-defining plates 57 which are supported in spaced, aligning relationship with each other by means of a pair of circular supports 59 which are spaced apart and insulated from each other by glass spacers 60 and 61 and are held in assembled relationship by washers 62 and rivets 63. The dimensions of the aligning collimating slits 65 in the slit defining plates 57 are primarily determined by the resolution required or desired, the narrower slits providing better resolution. Intermediate the two collimating slits 65, there are provided a pair of beam centering electrodes 67, each of which comprises a right angle shaped, metallic member, spot-welded or otherwise integrally attached to a suitable supporting plate 69 approximately semi-circular in outline. The plates 69 are in turn supported in proper position to center the electrodes 67 relative to the aligned collimating slits 65 by means of the glass spacers 60 and 61 and the rivets 63, as illustrated particularly in Figs. 2, 3, and 4.

In order that the filament 33 may be utilized for the thermionic production of positive, metallic ions, it has been found necessary to either manufacture the filament from the particular metal involved or to coat the filament with a suitable compound of that metal, for instance, the oxide of the metal. In the case of uranium, the manufacture of a filament of that metal is

not practical for making routine measurements as a check on manufacturing operations, because of the time required and because of the inherent difficulties in working uranium. As a result, composite, oxide coated filaments have been resorted to, using a coiled filament of a metal such as tungsten, tantalum, molybdenum, or the like, for the metallic part of the composite structure.

In coating the filament with oxide, for example U_2O_3 or UO_2 , a binder is required, and this binder must possess certain exacting, and to some extent conflicting, properties. Particularly, the binder should be solid at room temperatures; it should have a vapor pressure at room temperatures sufficiently high that it can be quickly pumped off in vacuum; the melting point should be low, of the order of about 60° to 90° C.; and finally, the vapor pressure at the melting point should be sufficiently low that the binder does not evaporate too rapidly during the coating operation. The following organic compounds have been found to satisfy all of the above requirements:

	M. P., °C.	Vap. Press. at M. P. mm. Hg	Vap. Press. at 20° C. mm. Hg
Diphenyl $C_6H_5C_6H_5$ ...	69-71		1.5×10^{-2}
30 Acenaphthene $C_{10}H_6$ -(CH_2) ₂ .	95	2.5	1.35×10^{-2}

¹ Estimated.

One particularly satisfactory coating procedure is as follows: A thin paste is made by stirring together powdered UO_2 and melted binder. The metallic filament to be coated, having previously been cleaned, is heated in air (by the passage of electrical current) to a temperature just above the melting point of the binder. The UO_2 paste is then applied to the filament with a one millimeter glass rod or other convenient applicator. If the filament is at the proper temperatures when this is done, the oxide paste runs around and completely fills in the space between the turns of the helix. The coated filament is then heated in vacuum at a sufficient temperature to drive off the binder and the final result is an oxide coating of uniform thickness having a reasonably smooth, sintered appearance.

In the making of abundance ratio measurements by the use of the above described type thermionic ion source, it is necessary to manufacture a new coated filament for each measurement. This results from the fact that there is some contamination of the filament metal by the uranium oxide when the filament is heated to a sufficient temperature to effect positive ion liberation. Whether this is due to an alloying of the filament with the oxide, or whether it is due to some other reason, is not known, but the effect is quite evident. The cooperating grinds 9 and 13 and the adjustable support for the focusing electrodes 45 greatly facilitate the disassembling, reassembling, and adjustment of the apparatus as the different tests are made. The cooperating grinds 9 and 13 also permit convenient and accurate adjustment of the relative position of the thermionic ion source 11 and the beam collimating and centering structure 21.

During the operation of the spectrometer, it has been found desirable to provide means whereby the electric potentials applied to the two focusing electrodes 45 can be varied independently within reasonable limits. It is also desirable that

the potentials applied to the beam centering electrodes 67 shall be susceptible of some relative variation. The circuit illustrated in Fig. 6 includes elements whereby these and other control potentials can be provided, but it will be understood that this is merely an illustrative type of circuit.

The circuit of Fig. 6 comprises essentially two main portions: a low voltage A.-C. filament supply, and a high voltage D.-C. source for the various control potentials required. The low voltage A.-C. filament supply includes a voltage stabilizing transformer 71, which may conveniently be energized from a 110 volt 60 cycle source, a variac 72, and a center tap filament transformer 73 which serves the additional function of insulating the filament supply from the control potential. An ammeter 74 may be included in the filament circuit, if desired.

The high voltage D.-C. portion of the circuit is of the voltage divider type. It includes a 2500 volt stabilized rectifier type supply 70 which is energized from a 110 volt 60 cycle source, and a main voltage divider section having a 1.5 meg-ohm fixed resistor section 75, a .5 megohm section 76 tapped at 50,000 ohm intervals, and a 50,000 ohm potentiometer section 77, the center tap of which is grounded as illustrated at 78. A voltmeter 79 and a stabilizing condenser 80 of about 2 microfarad capacity are connected across the output leads 78 and 81. The output lead 81, which is the positive lead, connects to the center tap of the filament transformer 73 thus maintaining the coated filament, thermionic ion source at the desired high positive potential.

The voltage sources for the focusing electrodes 43 and the several elements of the beam collimating and beam-centering structure 21 are also connected at one end to the positive output lead 81. In order that independently adjustable potentials may be supplied to the two focusing electrodes 43 the circuit from the output lead 81 to each electrode 43 includes a source of D.-C. potential 83 which may comprise a battery of about 150 volts, and a variable resistor 85 having a total resistance of about 20,000 ohms. Voltmeters 86 may be connected as illustrated to provide visual control of the focusing electrode potentials. By this arrangement the focusing electrodes 43 can be maintained at potentials differing from each other and from the filament 33 by values up to the potential of the battery 83, or other auxiliary potential source.

The analyzer tube 23 and the two collimating slit defining electrodes 57 are grounded, and by means of a double pole double throw switch 87, a fixed resistor 88, and a variable resistor 89 connected as illustrated, it is possible to ground either of the beam centering electrodes 67 and to apply a D.-C. potential of the order of 0 to 250 volts above ground to the other electrode. The fixed resistance 88 may conveniently be of the order of 10 megohms and the variable resistor 89 may be of the order of 1 megohm.

In the operation of spectrometer apparatus of this character, a high degree of vacuum appears to be required in order to make possible good resolution of the isotopic constituents of the sample under test. In the particular spectrometer described above, it was found necessary to provide a vacuum of approximately 4×10^{-7} m. m. of mercury in order to obtain good resolution of the 235 and 238 uranium isotopes.

In the making of measurements with the de-

scribed apparatus, the first step will, of necessity, be the preparation of a suitable ion emitting filament, as by coating the filament 33 with a mixture of binder and an oxide sample of the material under test. Following this operation the focusing electrodes 43 will be adjusted to accurately locate the filament 33 relative thereto and thus assure that the desired ion beam will be obtained. The filament and focusing electrode assembly 11 may then be introduced into the interior of the main body 7 of the spectrometer through the agency of the cooperating male and female grinds 9 and 13. These grinds have a further advantage in that they permit relatively close adjustment of the position of the thermionic ion source structure 11 and the collimating and beam centering assembly 21. The seal at the grinds may be improved by the application of a thin ribbon of vacuum sealing wax along the meeting edges of the parts. The electrical connections to the focusing electrodes 43 can be attached in place by reaching through the evacuation lead 41 or may be attached while the electrodes are outside of the glass envelope 1, a spring lead being employed so that the leads will contract when the electrode is in place.

The spectrometer may now be evacuated, holes 91 in the analyzer tube 23 facilitating rapid pumping of the entire structure, and during this operation the filament 33 may be heated so as to vaporize the binder and effect the formation of the oxide coating thereon. The evacuation should be continued until the necessary low pressure is obtained within the tube. A McLeod, hot filament, vacuum gauge, not shown, or equivalent apparatus, may be employed for determining the vacuum pressure within the spectrometer. At the conclusion of the pumping operation, the apparatus is in condition to proceed with the determination of the abundance ratio or other tests. The focusing electrode potential controls provided make possible easy and rapid focusing of the thermionic ions liberated by the filament 33 into a beam and the directing of that beam onto the nearer collimating slit 65, and the means provided for controlling the relative potential of the beam centering electrodes 67 makes possible accurate centering of the ion beam in its passage through the collimating structure. Measurements made with filaments coated with uranium dioxide powder, in accordance with the previously described procedures, show that at least three types of ions are liberated at filament temperatures of the order of 1700 to 1800° C. These ions include U^+ , UO^+ , and UO_2^+ , and isotope abundance ratio measurements may be made on any one of the liberated ions.

In the foregoing there are described the features of an improved mass spectrometer which has particular utility in the determination of abundance ratios of the isotopes of the heavier elements, especially uranium. The apparatus of the present invention is simple in design, and is relatively easy to operate due in part to the novel improved ion source which is included therein and in part to the combination of that ion source with the novel collimating and beam centering structure disclosed. The features of the present invention considered to be new are particularly pointed out in the appended claims.

What is claimed is:

1. A thermionic ion source for a mass spectrometer comprising a heater filament, support means for said filament, a coating on said filament which will liberate ions of the desired char-

acter when heated to a predetermined temperature, a pair of electrodes for focusing and directing the ions produced by said source, and means supporting said electrodes in opposed, outwardly flared relationship adjacent to said coated filament, said support means insulating said electrodes from said coated filament and including means to adjust the position of said electrodes relative to said coated filament attached to the electrodes, and means to apply a positive potential to the electrodes.

2. A thermionic ion source for a mass spectrometer comprising a heater filament, a coating on said filament which will liberate ions of the desired character when heated to a predetermined temperature, support means for said filament, a pair of flat electrodes for focusing and directing the ions produced by said source, and means supporting said electrodes in opposed, outwardly flared relationship whereby said electrode define the sides of a dihedral angle with said filament located adjacent to the vertex thereof, said electrode support means including means for insulating said electrodes from said coated filament and means to adjust the position of said electrodes relative to said coated filament, and means to apply a positive potential to the electrodes.

3. A thermionic ion source for a mass spectrometer comprising a helical filament, a coating on said filament which will liberate ions of the desired character when heated to a predetermined temperature, support means suspending said filament from the ends thereof, a pair of flat, sheet metal electrodes for focusing and directing the ions produced by said source, and means supporting said electrodes in opposed, outwardly flared relationship whereby said electrodes define the sides of a dihedral angle with said filament located adjacent to the vertex thereof, said electrode support means insulating said electrodes from said coated filament and from each other, and including means to adjust the position of said electrodes relative to said coated filament connected to the electrodes, and means to apply an independently adjustable positive potential to each of the electrodes.

4. A thermionic ion source for a mass spectrometer comprising a glass tube having a press seal in one end thereof, a pair of spaced apart filament supports contained in said press seal, a helical filament suspended on said filament supports, a coating on said filament which will liberate ions of the desired character when heated to a predetermined temperature, a pair of flat electrodes for focusing and directing the ions produced by said coated filament, means supporting said electrodes on said glass tube in outwardly flared relationship, so as to define the sides of a dihedral angle, said coated filament

being located adjacent to the vertex of said angle, and said electrode support means including clamps which engage said tube and which permit adjustment of the position of said electrodes relative to said coated filament, and means to apply a positive potential to the electrodes.

5. In combination in a mass spectrometer, a thermionic source of positive ions, ion beam collimating means, said source and said means defining a longitudinal axis, and means along said axis and between said source and said collimating means for focusing the ions produced by said source into a beam and for directing said beam into said collimating means, comprising a pair of flat electrodes, means supporting said electrodes in opposed, outwardly flared relationship adjacent to the source of positive ions, said support means insulating said electrodes from said ion source and including means attached to the electrodes to adjust the position of said electrodes relative to the ion source, and means to apply a positive potential to the electrodes.

6. A thermionic source of positive ions comprising in combination: a cylindrical insulating support member, two rigid filament supports extending from within the cylindrical support member and secured thereto at one end, a coated filament connected between the filament supports, two flared electrodes mounted on the filament supports adjacent to the filament and insulated therefrom, said electrodes defining the sides of a dihedral angle, at least one movable circular clamp mounted upon the cylindrical support member, an adjusting element connected between each electrode and a clamp, and means to apply a positive potential to each of the electrodes.

7. A device for generating a beam of ions comprising, an ion source, and means to focus the ion source into a beam, said means comprising a pair of electrodes, and means supporting said electrodes in opposed, outwardly flared relationship adjacent to the ion source, said support means including means attached to the electrodes to adjust the position of said electrodes relative to the ion source and means to apply a positive potential to the electrodes.
